ABSTRACT OF THE DISCLOSURE

Toilet paper comprising a core impregnated with talc between two facing sheets of non-woven material. At least one of the sheets is an absorbent tissue while the other sheet is of polyethylene film.

BACKGROUND OF THE INVENTION**Field of the Invention**

This invention relates to a toilet paper and more particularly to a powdered toilet paper for making available an immediate supply of powder from toilet paper to a user's skin in the contact area for lubrication and drying effects.

Description of the Prior Art

Toilet papers have been devised for absorbing excrement from a user in a manner so as to allow for cleanliness and to prevent the soiling of garments. However, material such as talc used for drying and lubricating the user's skin is often not available or not convenient to use.

The present invention provides for a toilet paper which contains its own supply of powder which will feed itself to the skin of the user during use so as to dry, lubricate and protect the user's skin from chaffing while also serving to neutralize the chemical effects of the urine and feces thereafter.

Various types of toilet papers have been devised in the past which contain two layers of absorbent material and are arranged in a roll. None of the prior art provides for retaining a suitable layer of powder in the toilet paper adapted for convenient and efficient self-application onto the skin of the user.

SUMMARY OF THE INVENTION

It is therefore the primary object of the present invention to provide a toilet paper adapted to make available an immediate supply of powder from the toilet paper to the user's skin in the contact areas for lubrication and drying effects.

It is a further object of the invention to provide a toilet paper adapted for self-application of powder to the crotch area of a user at the time of use.

The construction of this invention features a composite layered toilet paper having a core of woodfluff impregnated with talc sandwiched between thin non-woven facing sheets. The toilet paper has a plurality of rows of small perforations for permitting the passage of talc onto the skin of the surface of the facing sheets and thence to the skin of the user.

Still further objects and features of this invention reside in the provision of a toilet paper that is simple in construction and manufacture, capable of being produced out of readily available materials and which can be manufactured at low cost to permit wide use and distribution.

2

These, together with the various ancillary objects and features of the present invention, which will become apparent as the following description proceeds, are attained by this powdered toilet paper having properties beneficial to skin, preferred embodiments of which are illustrated in the accompanying drawing, by way of example only, wherein:

Brief Description of the Drawing

FIG. 1 is a perspective view of a powdered toilet paper constructed in accordance with the concepts of the present invention;

FIG. 2 is a vertical sectional view taken along the plane of line 2—2 in FIG. 1 and

FIG. 3 is a view similar to FIG. 2 of a modified form of toilet paper.

Description of the Preferred Embodiment

With continuing reference to the accompanying drawing, wherein like reference numerals designate similar parts throughout the various views, reference numeral 10 is used to generally designate the powdered toilet paper constructed in accordance with the present invention. This toilet paper has three main component parts, including an outer facing sheet 12, a core 14 impregnated with talc or like powder 16, and an inner facing sheet 18.

The absorbent core 14 is made from a soft highly absorbent mat of wood fluff impregnated with powder 16 and sandwiched between the two thin non-woven absorbent facing sheets 12 and 18. An appropriate quantity of powder is evenly distributed on the top of the absorbent core 14 to form a layer. The facing sheets 12 and 18 are in the form of a non-absorbent soft, non-woven tissue capable of permitting the passage of talc from the core of the toilet paper to the surface of the facing sheets, thereby providing a "dry feel." The perforations 26 arranged in rows for separating the roll of toilet paper 10 into sheets also facilitate passage of talc into the surface of the facing sheets 12 and 18.

Referring now to the embodiment shown in FIG. 3 herein the outer facing sheet 32 is substituted for the facing sheet 12.

The outer facing sheet 32 is made of a suitable waterproof non-absorbent material, which is liquid impermeable, for preventing powder from passing entirely through the toilet paper. The sheet 32 is preferably made of a polyethylene film. When rolled up the facing sheet 32 contains the powder in the roll, only the inner facing sheet being used for contact with the user's skin. This form of the invention is not recommended for use with toilet facilities which feed into septic tanks.

A latitude of modification, substitution and change is intended in the foregoing disclosure, and in some instances some features of the present invention may be employed without a corresponding use of other features.

We claim:

1. Toilet paper comprising two facing layers of non-woven tissues, at least one of said facing layers being of an absorbent tissue capable of passing talc therethrough, a core of a soft mat of wood fluff provided with a layer of talc thereon between said facing layers, said facing layers and said core having rows of spaced perforations for facilitating separation of said toilet paper into sheets, said talc penetrating said perforations and said one facing layer to coat said one facing layer.

2. Toilet paper according to claim 1, wherein the other of said facing layers is non-woven thin film of polyethylene.
